UNITED STATES PATENT OFFICE.

JOHN S. COLDWELL, OF MILWAUKEE, WISCONSIN, ASSIGNOR TO THE CUTLER-HAMMER MFG. CO., OF MILWAUKEE, WISCONSIN, A CORPORATION OF WISCONSIN.

MECHANISM FOR FEEDING MATERIAL FROM ROLLS.

Application filed December 29, 1923. Serial No. 683,306.

To all whom it may concern:

Be it known that I, JOHN S. COLDWELL, a citizen of the United States, residing at Milwaukee, in the county of Milwaukee and 5 State of Wisconsin, have invented new and useful Improvements in Mechanisms for Feeding Material from Rolls, of which the following is a full, clear, concise, and exact description, reference being had to the accompanying drawing, forming a part of this 10 specification.

This invention relates to mechanisms for feeding material from rolls to receiving machines and more particularly to web feeding 15 mechanisms for printing presses.

Web feeding mechanisms for printing presses commonly include braking means for effecting a drag on the spindle of an active web roll to tension the material as 20 the same is drawn into the press. Heretofore considerable effort has been made to provide a mechanism for regulating such braking means to maintain the tension on the web substantially constant. However, 25 it has been found unnecessary in the operation of printing presses to maintain a constant tension on the web providing the variations in tension are gradual, and furthermore, it has been found very desirable to 30 effect a given reduction in the tension on the web when the roll is about to become exhausted.

The present invention has among its objects to provide a web tensioning device 35 which is adapted to automatically effect a predetermined reduction in the tension on the web when the roll is about to become exhausted and which automatically maintains the tension on the web between predetermined limits during unwinding of the 40 roll.

Another object is to provide a tensioning device of the aforesaid character wherein the weight of the web roll and the supporting mechanism therefor serves to control the 45 tension on the web.

Another object is to provide a web tensioning device of the aforesaid character which is capable of control from a remote 50 point such as the delivery end of the press for variation of the tension on the web.

Another object is to provide a web tensioning mechanism of the aforesaid character having its parts arranged to facilitate

removal of an exhausted roll and installation of a new roll.

Another object is to provide a web feeding mechanism, including a plurality of web tensioning devices of the aforesaid character having their parts arranged to facilitate pasting of the web of a reserve roll mounted on either of the devices to the web of an exhausted roll mounted on the other.

Another object is to provide a web feeding mechanism having improved margin adjusting means associated therewith.

Various other objects and advantages of the invention will hereinafter appear.

The accompanying drawings illustrate certain embodiments of the invention which will now be described, it being understood that the embodiments illustrated are susceptible of modification without departing from the scope of the appended claims.

In the drawings,

Figure 1 is an end elevational view of a web tensioning device embodying the invention.

Fig. 2 is a side elevational view of such device, certain parts thereof being shown in section.

Fig. 3 is a detail view of certain of the parts shown in Figs. 1 and 2.

Fig. 4 is a simplified end view of a web feeding mechanism including a plurality of the web feeding devices of the character shown in Fig. 1, and

Fig. 5 is an end elevational view of a part employed in the embodiment shown in Fig. 3, certain of the parts of the tensioning devices being shown in section.

Referring to Figs. 1 and 2, the same illustrate spindles 1 and 2 for supporting a web roll 3. The web roll 3 is provided with a hollow core member (not shown in the drawing) and spindles 1 and 2 are adapted to be inserted into opposite ends of said core member to support the web roll and to rotate therewith. Spindles 1 and 2 are carried by arms 4 and 5, respectively, rotatably mounted upon a shaft 6, supported at opposite ends by bearing pedestals 7 and 8, and said arms are fixed to each other by an intermediate member 9. Brake drums 11 and 12 are fixed to spindles 1 and 2, respectively, to rotate therewith and the former brake drum is provided with a cooperating brake shoe 13 while the latter is provided

with a cooperating brake shoe 14. Brake shoes 13 and 14 are pivotally secured to arms 15 and 16, respectively, which are fixed to shaft 6. As hereinafter set forth, power operated means is provided for rotating shaft 6 to vary the angular position of arms 15 and 16 for variation of the tension on the web and power operated means is also provided for adjusting arms 4 and 5 axially 10 on shaft 6 to effect margin adjustments of the web roll.

More specifically, spindle 1 is slidably keyed within a hub 11^a on brake drum 11 and said hub projects outwardly beyond said 15 brake drum in opposite directions. The left hand end of the hub 11^a is supported by a ball bearing 17 mounted on the upper end of arm 4 while the right hand end of said hub is supported by a ball bearing 18 carried by 20 a bracket 19 fixed to arm 4. As before stated, spindle 1 is slidably keyed within the hub 11^a and the same is adjustable axially therein by a screw 20 threaded into the left hand end of said hub. The inner end 25 of screw 20 has an enlarged head 21 fitting within a T slot in the end of spindle 1 and said screw has an adjusting hand wheel 22 fixed thereto and a locking hand wheel 23 threaded thereon for engaging the right hand end of hub 11^a. Spindle 2 is fixed 30 within the hub of brake drum 12 and the same is supported adjacent its right hand end by a ball bearing 24 mounted on the upper end of arm 5 while the left hand end 35 thereof is supported by a ball bearing 25 carried by an arm 26 fixed to arm 5.

Springs 27 and 28 tend to move arms 4 and 5 in a counter-clockwise direction with 40 respect to arms 15 and 16, as shown in Fig. 1. Spring 27 is held under compression between bracket 19 and a cap member 29 while spring 28 is held under compression between bracket 26 and the cap member 30. Cap members 29 and 30 each have an adjusting screw 31 associated therewith, the screw associated with the former cap member being threaded into a lug 15^a on arm 15 and the screw associated with the latter cap member being threaded into a lug 16^a on arm 16. Each of the arms 15 and 16 has a lever 32 pivotally secured thereto and each of said arms is provided with a projecting lug having a drilled opening therein for receiving a pin 33. The inner end of the pin 33 associated with arm 15 is arranged to abut bracket 19 while the inner end of the pin 33 associated with arm 16 is arranged to abut bracket 26. As shown in Fig. 3, the levers 32 are each provided with a cam surface 34 and upon movement of said levers from the position indicated in full lines in Fig. 3, said cam surfaces are adapted to move the pins 33 inwardly, to cause arms 4 and 5 to move in a counter-

clockwise direction with respect to the arms 15 and 16 for disengagement of brake drums 11 and 12 from their respective brake shoes. Each of the levers 15 and 16 is provided with a spring clip 35 for holding its associated lever 32 in the position indicated by full lines in Fig. 3.

The function and operation of the afore-described web tensioning mechanism will now be more fully set forth. Assuming that

the web roll is in the position indicated in full lines in Fig. 1, it is apparent that the weight of the web roll together with the weight of arms 4 and 5 and the parts carried by the latter, is resolved into two component forces. One of such forces is in a line extending between the axis of web roll 3 and the axis of shaft 6 and the other is at right angles to the former force and tends to hold the brake drums 11 and 12 in engagement with their respective brake shoes. It will be observed that the ratio of such forces is dependent upon the angular position of arms 15 and 16. Neglecting the weight of arms 4 and 5 and the parts carried thereby, the force tending to hold brake drums 11 and 12 in engagement with their respective brake shoes is determined by the weight of the web roll and it is apparent that during unwinding of the web roll such force tends to produce a tension on the web which varies in accordance with the diameter of the roll. Neglecting the weight of the roll the weight of the arms 4 and 5 and the part carried thereby tends to hold brake drums 11 and 12 in engagement with their respective shoes to produce a braking effect on the web roll which is determined by the degree of compression of springs 27 and 28. The braking effect due to the weight of the arms 4 and 5 and the parts carried thereby, produces a relatively slight tension on the web when the roll is of large diameter but as the diameter of the roll decreases the tension on the web due to such braking effect increases. Also, as the roll diameter decreases an increasing force, due to the tension on the web, tends to move the brake drums 11 and 12 out of engagement with their respective shoes and when the roll is of relatively small diameter such force tends to counteract the braking effect due to the weight of the arms 4 and 5 and the parts carried thereby.

From the foregoing it will be observed that when the roll is of large diameter the tension on the web is almost entirely determined by a component due to the weight of the web roll while when the roll is about to become exhausted the tension on the web is determined almost entirely by a component due to the weight of the arms 4 and 5 and the parts carried thereby. Thus, the initial tension on the web can be controlled by varying the angular position of the arms

120
125
130

4 and 5 while the final tension on the web can be determined by varying the degree of compression of springs 27 and 28. In connection with the foregoing it should be noted that during starting of the press the braking means can be rendered ineffective and thus prevent breaking of the web, by moving the levers 32 to the position indicated in dotted lines in Fig. 3.

10 As before stated, power operated means is provided for rotating shaft 6 to vary the angular position of arms 15 and 16 and, as best shown in Fig. 1, such means includes a motor 36 mounted upon a bracket carried by pedestal 8. Motor 36 is operatively connected to a counter shaft 37 through the medium of a spur gear 38 and a pinion 39 and shaft 6 is driven from said countershaft through the medium of a worm wheel 40 and worm 41. Motor 36 can be controlled from any desired point, such as the delivery end of the press and the same can be also controlled from a point in proximity to the tensioning device to facilitate installation 25 of the web rolls. In installing a web roll the motor 36 is operated to bring the spindles 1 and 2 on a level with the core member of the web roll, the latter being on the floor. The web roll is then rolled into position 30 between the spindles 1 and 2 and upon alignment of the spindles with the core member the same are forced into such core member by means of screw 20. The motor 36 is then operated to elevate the roll to the desired 35 position.

Also, as before stated, power operated means is provided for adjusting arms 4 and 5 axially on shaft 6 to effect margin adjustments of the web roll. As shown in Fig. 2, such means comprises a motor 42 mounted 40 upon a bracket fixed to a bearing pedestal 8 and adapted to drive a screw shaft 43 through the medium of a worm wheel 44 and worm 45. Screw 43 has its left end rotatably mounted within a suitable bearing on pedestal 8, the same being held against axial movement within said bearing, and the right hand end of said screw extends into a nut carried by a bracket 47. Bracket 47 is mounted upon the connecting member 9, between arms 4 and 5 by a cap member 48 and the same is held against axial movement on said member but is free to rotate thereon. Thus it is apparent that upon reverse operations of motor 42, screw 43 will effect axial adjustments of arms 4 and 5 on shaft 6 to effect margin adjustment of the web roll 3.

Referring now to Fig. 4, the same illustrates a pair of web tensioning devices A and B of the character hereinbefore described, such devices being arranged side by side and in a reversed relation. The shafts 6 of the tension devices are supported at 60 opposite ends by pedestals C, one of which is illustrated in Fig. 4 and the driving motor 36 associated with tensioning device A is mounted on the rear pedestal while the driving motor 36 associated with the mechanism B is mounted on the front pedestal. 70 With the tensioning devices arranged in this manner it will be observed that a reserve web roll can be mounted on either of the devices while the roll on the other device is active, and that the extremity of the reserve web roll can be readily connected to the web proceeding from the active roll prior to exhaustion of the latter. In connecting the web of the reserve roll to the web of the active roll the press is stopped and the 80 web rolls are brought to the position shown in Fig. 4. Paste having been previously applied to the outer surface of the extremity of the reserve web roll, it is apparent that such extremity can be readily connected to the web proceeding from the active roll. After connection of the webs the press is started and the web of the active roll is severed. During such pasting operations the brake drums are released from their respective brake shoes by means of the levers 32 and after the press is started the drums associated with the new roll are moved into engagement with their respective brakes by returning such levers to normal position. 90

With the tension devices arranged as shown in Fig. 4, the margin adjusting means is arranged to effect simultaneous margin adjustments of both of the devices. The connecting members 9 of the tensioning devices 100 are secured together by a bracket 49 (Fig. 5), such bracket being provided with a screw threaded part 50 for receiving the margin adjusting screw 43.

What I claim as new and desire to secure by Letters Patent is:

1. A mechanism for tensioning material drawn from a web roll comprising means for imposing a frictional drag on said roll and for rendering such drag proportional to the weight of said roll, said means including means for resolving the weight of said roll into component forces, one of which is effective to control such drag. 110
2. A mechanism for tensioning material drawn from a web roll, comprising means for imposing a frictional drag on said roll and for rendering such drag proportional to the weight of said roll, said means including means adapted to resolve the weight of said roll into component forces, one of which is effective to control such drag, said latter means being adjustable to vary the ratio of such component forces. 115
3. In a mechanism for tensioning material drawn from a web roll, in combination, a brake drum to be fixed to said roll to rotate therewith, a brake shoe for engaging said drum to tension the web as the same is drawn from said roll, and supporting means 120
- 65

- 4
- for said roll adapted to resolve the weight thereof into component forces, one of which acts to hold said drum in engagement with said shoe, said means being adjustable to 5 vary the ratio of such component forces.
4. In a mechanism for tensioning material drawn from a web roll, in combination, a brake drum to rotate with said roll, a cooperating brake shoe for engaging said 10 drum to tension the material drawn from said roll and means for holding said drum in engagement with said shoe under the action of the weight of said roll and in a direction at an angle to the vertical, said 15 means being adjustable to vary such angle for variation of the tension on the web.
5. In a mechanism for tensioning material drawn from a web roll, in combination, supporting means for the web roll rotatable 20 about an axis to one side of said roll, a brake drum associated with said roll to rotate therewith and a brake shoe for engaging said drum, said shoe being adjustable to vary the angular position of said roll 25 with respect to said axis for variation of the pressure of said drum on said shoe.
6. In a mechanism for tensioning material drawn from a web roll, in combination, a supporting frame for the web roll including 30 alined spindles to be inserted into opposite ends of the roll to support the same and to rotate therewith, said frame being rotatable about an axis parallel to said spindles, a brake drum fixed to one of said spindles 35 and a brake shoe for engaging said drum to tension the web as the same is drawn from said roll, said shoe being adjustable to vary the angular position of said frame for variation of the tension on the web.
- 40 7. In a mechanism for tensioning material drawn from a web roll, in combination, a supporting frame for the web roll including alined spindles to be inserted into opposite ends of the roll to support the same and to rotate therewith, said frame being rotatable about an axis parallel to said spindles, a brake drum fixed to one of said spindles, a cooperating brake shoe for engaging said 45 drum to tension the material, proceeding from the roll and a supporting arm for said 50 brake shoe, said drum tending to move towards said shoe under the action of the weight of said frame and the roll mounted thereon, and said arm being movable to 55 vary the angular position of said frame.
8. In a mechanism for tensioning material drawn from a web roll, in combination, a rotatable frame including alined spindles to be inserted into opposite ends of the roll to 60 support the same and to rotate therewith, a brake drum fixed to each of said spindles, a brake shoe associated with each of said drums and adapted through engagement with the latter to hold said frame in different angular positions and rotatable sup- 65 porting arms for said shoes, said frame and said arms being rotatable upon a common axis parallel to the axis of said roll.
9. In a mechanism for tensioning material drawn from a web roll, in combination, a 70 supporting frame for said web roll, including alined spindles for supporting the web roll and to rotate therewith, said frame being rotatable about an axis parallel to said spindles, a brake drum fixed to one of said 75 spindles, a cooperating brake shoe for engaging said drum to tension the material drawn from said roll, a rotatable supporting arm for said shoe and means for moving said frame with respect to said arm to 80 disengage said drum from said shoe.
10. In a mechanism for tensioning material drawn from a web roll, in combination, a supporting shaft, a frame rotatably mounted on said shaft and including spindles to be inserted into opposite ends of the web roll to support the same and to rotate therewith, said spindles being arranged parallel to the axis of said shaft, a 85 brake drum fixed to one of said spindles, a 90 cooperating brake shoe, a supporting arm for said brake shoe fixed to said shaft and means for rotating said shaft to vary the angular position of said arm.
11. A mechanism of the character described, including separate frames for supporting a pair of web rolls in a parallel relation, each of said frames being provided with alined spindles for receiving a web roll therebetween and being rotatable about an axis parallel to said spindles to provide for positioning of said rolls with their peripheries adjacent each other during sealing of the web extremity of a roll mounted on either of said frames to the web of a roll 105 mounted on the other.
12. A mechanism of the character described including separate frames for supporting a pair of web rolls in a parallel relation, each of said frames being provided with alined spindles for receiving a web roll therebetween and being rotatable about an axis parallel to said spindles to facilitate installation of the web rolls on said frames and to provide for positioning of said rolls adjacent each other during sealing of the web extremity of either of said rolls to the web of the other.
13. A mechanism of the character described including separate frames for supporting a pair of web rolls in a parallel relation, each of said frames being provided with alined spindles for receiving a web roll therebetween and being rotatable about an axis parallel to said spindles, tensioning means associated with each of said spindles, said means being adapted to hold said frames in varying angular positions for variation of the tension on the web and being also adapted to move said frames to a 120 125 130

- position wherein said rolls are adjacent each other to facilitate sealing of the web extremity of a roll mounted on either of said frames to the web extending from the roll mounted on the other of said frames.
14. In a mechanism of the character described, in combination, separate frames for supporting a pair of web rolls in a parallel relation, one of said rolls having its web 10 extending into a receiving machine from the side thereof adjacent the other of said rolls and the latter being arranged to unwind in a direction opposite to the unwind- 15 ing of the direction of the former and having an adhesive applied to the web ex- tremity thereof, each of said frames being rotatable about an axis parallel to said spindles to provide for positioning of said rolls adjacent each other to facilitate seal- 20 ing of the web extremity of the latter web roll to the web proceeding from the former.
15. A mechanism of the character described including separate frames for supporting a pair of web rolls in a parallel relation, each of said frames being provided 25 with aligned spindles for receiving a web roll therebetween and being rotatable about an axis parallel to said spindles, a brake drum fixed to one of the spindles of each 30 of said frames, cooperating brake shoes for said drums, supporting arms for said brake shoes, power operated means for varying the angular position of said arms, and power operated means for effecting axial 35 adjustment of said frames.
16. In a mechanism for tensioning ma- terial drawn from a web roll, in combina-
- tion, a supporting frame for said roll including aligned spindles for supporting the web roll and to rotate therewith, said frame being rotatable about an axis parallel to 40 said spindles, a brake drum fixed to one of said spindles, a cooperating brake shoe for engaging said drum to tension the ma- 45 terial drawn from said roll, said drum tending to move towards said brake shoe under the action of the weight of said frame and said roll, means for adjusting said brake shoe to vary the angular position of said frame, and auxiliary means tending to 50 move said drum out of engagement with said shoe.
17. In a mechanism for tensioning mate- rial drawn from a web roll, in combination, 55 a supporting frame for the roll including aligned spindles to support the roll and to rotate therewith, said frame being rotatable about an axis parallel to said spindles, a brake drum fixed to one of said spindles, a brake shoe for engaging said drum to 60 tension the material drawn from said roll, a rotatable supporting arm for said shoe, said drum tending to move toward said shoe under the action of the weight of said roll and said frame, and said arm being ad- 65 justable to vary the angular position of said frame and auxiliary means associated with said arm and tending to move said frame in a direction to disengage said drum from said shoe, said latter means being adjust- 70 able to vary the effectiveness thereof.

In witness whereof, I have hereunto sub-
scribed my name.

JOHN S. COLDWELL.
